UNITED STATES PATENT OFFICE

2,245,439

REFRIGERATING APPARATUS

Harry B. Hull, Dayton, Ohio, assignor to General Motors Corporation, Dayton, Ohio, a corporation of Delaware

Original application July 31, 1933, Serial No. 682,977. Divided and this application February 23, 1939, Serial No. 257,920

3 Claims. (Cl. 62—8)

This application is a division of my copending application Serial No. 682,977 filed July 31, 1933, now Patent No. 2,150,224, which is a continuation in part of application Serial No. 465,019 filed June 30, 1930.

This invention relates to refrigerating apparatus and more particularly to apparatus for cooling air, as, for instance, in rooms or the like.

One of the objects of the present invention is to provide an improved apparatus for cooling and circulating air in rooms or the like.

Another object of this invention is to provide an improved apparatus which automatically circulates the air in the room, reduces the humidity and maintains said air at a predetermined temperature.

Further objects and advantages of the present invention will be apparent from the following description, reference being had to the accompanying drawings, wherein a preferred form of the present invention is clearly shown.

In the drawings:

Fig. 1 is a vertical cross sectional view, semi-diagrammatic in character, of a room cooler or air conditioner embodying my invention;

Fig. 2 is a view in elevation of an apparatus for controlling the operation of the air conditioners herein disclosed in accordance with the temperature of the air;

Fig. 3 is a cross sectional view of a water valve which may be used for controlling the flow of water through the water coils; and

Fig. 4 is a diagrammatic representation of the application of the device shown in Fig. 2 to air conditioners of the general type disclosed in Fig. 1.

In the particular embodiment shown in Fig. 1 air is circulated through a cabinet 160 by means of an electrically operated fan or means 162 which draws the air through louvers 164, through an air treating zone 166 and discharges the treated air through a screened opening 168 provided in the top of the cabinet 160. A plurality of cooling coils 170 connected in series by means of pipes are adapted to cool the air to a temperature below its dew point so that when the air is rewarmed it will be at the desired relative humidity, which rearming may be accomplished by a plurality of coils 175 disposed above the coils 170 thus preventing cold saturated air from striking occupants of the room. Refrigerant is circulated in a closed path through the coils 170 by means of a refrigerant circulating element 180 under the control of an expansion valve 181. The element 180 delivers the liquid refrigerant

5 through pipe 185 and withdraws the gaseous refrigerant through pipe 187. The element 180 comprises a compressor 190 operatively connected with a motor 191 by belt 192. The motor 191 is controlled by a switch 193 actuated by a thermostat 194 in response to the temperature of pipe 181. The compressor 190 compresses the gaseous refrigerant and delivers it to a water cooled condenser 195 through pipe 196. The gaseous refrigerant is liquefied in the condenser 195 and from 10 which it is delivered through pipe 185 to the coils 170. The heating coils 175 are heated by water passing through coil 200 used for liquefying the refrigerant in the condenser 195. The coil 200 15 used for liquefying the refrigerant is provided with an inlet 201. The water then passes through pipe 203, heating coils 175 to an outlet pipe 210. The water inlet 201 may be connected to any suitable water pressure system while the outlet pipe 210 may be connected to the water waste system. In the apparatus shown in Fig. 1, the 20 electrically operated fan 162 draws the air through the louvers 164 and some air through cutaway portions of the cabinet 160 as shown at 25 211. The air is then forced through an opening 215 provided in a drip or moisture pan 216 whence the air is forced along the loops of coils 170 and coils 175 and is then discharged through the screened opening 168. A bonnet or hood 219 is 30 provided to prevent moisture from the coils from dripping through the opening 215. A thermostatic switch of the type shown in Fig. 2 may be employed for controlling the operation of the electrically operated fan 162 and the flow of current to the contacts of the switch 193 as diagrammatically shown in Fig. 4 in which fan 281 corresponds to the fan 162 shown in Fig. 1. Thus it will be noted that refrigerant is circulated 35 through the air treated zone for cooling the air to a temperature below its dew point and that the air is later rewarmed so that the discharged air will have the desired relative humidity and that in rearming said air a part of the heat of liquefaction of said refrigerant is utilized for 40 heating the air.

Reference is hereby made to my above mentioned patent in which additional modifications are shown and described which are in many respects similar to the modifications shown in Fig. 1 45 of this application. Fig. 4 is a diagrammatic representation to indicate how the controls shown in Figs. 2 and 3 are applied specifically to an apparatus of the type shown in Fig. 3 of my above mentioned patent. It is to be understood that 50 the same controls can be applied to the modifica-

tion shown in Fig. 1. Similar references characters have been used in Fig. 4 of this application and Fig. 3 of my above mentioned patent so that the various parts in the two figures can be readily identified without further description.

The controls are preferably set so that the evaporators do not attain a temperature below the freezing point of water, thus preventing the accumulation of frost on the evaporators.

In order to provide means for controlling the operation of the electrically driven fan 281 and the electrically operated valve 284 and for controlling the flow of current to contacts 310 of switch 300 a thermostatic switch 312 has been provided. As shown in Fig. 2 the thermostatic switch 312 is provided with a bimetallic thermostatic coiled blade 314 and a plurality of mercury containing tubes or bulbs 315 and 316. The switch 312 is adapted to control the valve 284 and the fan 281 at a predetermined room temperature which may be determined by the position of the adjustable handle or indicator 320 of switch 312. As shown in Fig. 3 the electrically operated valve includes a magnet winding 322 and a movable core 323 which carries the valve proper, 325. The valve 284 is provided with an inlet passage 327 in a casing 328 and an outlet passage 329. When the magnet winding 322 becomes energized, the core 323 will be moved upwardly to move the valve proper 325 from the seat to thus allow unrestricted communication between the inlet passage 327 and the outlet passage 329 to thus permit the circulation of water through the coils 283. The switch 312 is adapted to place the magnet winding 322 of valve 284 and the motor 330 which operates the fan 281 in circuit with the power mains 332 and 333 when the temperature of the room attains a predetermined value, for instance, the temperature as indicated by the indicator 320. Thus when the temperature of the room reaches the point indicated by the indicator 320, the switch 312 will allow the current to be supplied to the magnet winding 322 of valve 284 and to the motor 330 to cause water to circulate in coils 283 and to cause air to circulate through the air treating zone 276 by the operation of fan 281. The circuit through the magnet winding 322 of valve 284 and through the motor 330 is as follows: Power main 333, wire 340, magnet winding 322, wire 341, motor 330, wire 342, contacts of mercury containing tube 315 which contacts are completed by the engagement of the mercury drop 345 therewith, and wire 347 which is connected to power main 332. If the temperature of the room continues to increase, for instance, to an increase of five degrees over the desired temperature as indicated by indicator 320, the bimetallic thermostatic blade 314 will cause the rotation of the mercury containing tube 316 to thus cause the mercury drop 350 to engage the contacts of the mercury containing tube 316 to complete a circuit through the contacts 310 of switch 300 to thus allow current to flow from the power mains to the motor 296 to thereby actuate the compressor 295. The circuit through the motor 296 is power main 333, wire 352, motor 296, contacts 310 of switch 300, wire 355, wire 354, contacts of mercury containing tube 316 and wire 356 which is connected with power main 332. From the foregoing it will be noted that when the temperature of the room attains a predetermined amount, above the setting of the indicator 320 of switch 312, the electrically operated fan 281 and the electrically operated valve

284 will be actuated to thus cause the flow of water in the coils 283 and the circulation of air through the air treating zone 276. However, should the water flow apparatus and the fan 281 be unable to maintain the desired temperature in the room to be cooled the refrigerating element 290 would be rendered operative to supply refrigerant to the coils 287 to thus reduce the temperature in the room to the temperature indicated by the indicator 320 of switch 312. When the temperature of the room is reduced to a temperature below that indicated by the means 320, the thermostat 314 will cause the rotation of mercury containing tube 316 to separate the mercury drop 350 from the contacts of the tube 316 to thus interrupt the flow of current to the motor 296 to thereby render the refrigerant circulating element inoperative. In the event the temperature of the room should fall below the desired temperature, as indicated by means 320 of switch 312, by the operation of the water flow apparatus and fan alone, the thermostat 314 will actuate the mercury containing tube 315 to thus separate the mercury drop 345 from the contacts of mercury tube 315 to thus interrupt the circuit to the motor 330 and to the magnet winding 322 of valve 284 to thus close the valve to thus prevent the circulation of water in the coils 283 and render the fan 281 inoperative. By this construction the cooling medium supplied to the banks of coils 283 and 287, extending across the cooler chamber 275, is independently and automatically varied so that the cooling effect of each bank on the air is varied in accordance with refrigeration demands.

If desired, the water inlet pipe 306 may be provided with a manually operable valve 500 as shown in Fig. 4, so that the fan 281 may be caused to operate to create an air current in the room without any cooling whatsoever merely by closing the manually operable valve 500 and by operating the manual switch 501 placed across the leads to the automatic control 312. Under such conditions, the pointer 320 should be adjusted to a temperature higher than any temperature likely to be reached by the air in the room. When under such setting and condition, the motor 330 will operate continuously and water will be prevented from flowing through the coil 283 by the valve 500, and no refrigerant will flow through the coil 287, because the control 312 is adjusted above the normal range of the air in the room.

While the form of embodiment of the present invention as herein disclosed, constitutes a preferred form, it is to be understood that other forms might be adopted all coming within the scope of the claims which follow.

What is claimed is as follows:

1. Air conditioning apparatus for a room or the like comprising in combination, a cabinet adapted to be mounted within the room, an air treating zone in the upper portion of said cabinet, a refrigerant evaporator in said zone, a water circulating coil in said zone, air circulating means disposed beneath said zone, a condensate collecting shield disposed between said air treating zone and said air circulating means, an air inlet opening in said casing adjacent said air circulating means, an air discharge opening above said air treating zone, refrigerant liquefying means in refrigerant flow relationship with said evaporator, means for circulating water in thermal exchange relationship with at least a portion of said refrigerant liquefying apparatus, and means whereby the water flowing in thermal exchange

with said portion flows through said water circulating coil.

2. An air conditioning refrigerating apparatus adapted to dehumidify air for comfort comprising a compressor, condenser and evaporator in refrigerant flow relationship, a water coil, blower means circulating air to be conditioned over said evaporator and said water coil, a blower motor driving said blower means, a compressor motor driving said compressor, a blower motor switch, a compressor motor switch, an expansion valve at the inlet of said evaporator, a thermostatic bulb at the outlet of said evaporator, said valve and

5 bulb cooperating with said compressor motor switch to maintain the temperature of said evaporator above the freezing point of water and below the dew point of air flowing over said evaporator, and means for circulating water flowing through said water coil in thermal exchange relationship with said condenser.

10 3. In the apparatus set forth in claim 2, a cabinet adapted to be mounted within the space to be conditioned, and means for supporting said evaporator, said water coil and said blower means within said cabinet.

HARRY B. HULL.
